CLAIM

The ornamental design for an iron, as shown and described.

DESCRIPTION

FIG. 1 is a perspective view of an iron according to a first embodiment of the present design.

FIG. 2 is a top plan view of an iron as seen in FIG. 1.

FIG. 3 is a bottom plan view of an iron as seen in FIG. 1.

FIG. 4 is a left side elevation view of an iron as seen in FIG. 1.

FIG. 5 is a right side elevation view of an iron as seen in FIG. 1.

FIG. 6 is a front elevation view of an iron as seen in FIG. 1; and,

FIG. 7 is a rear elevation view of an iron as seen in FIG. 1.

The broken lines in FIGS. 1 through 7 depicting an electrical cord are for illustrative purposes only and form no part of the claimed design.
